UNITED STATES PATENT OFFICE.

CAMPBELL SCOTT AND WILLIAM DEATS, OF YONKERS, NEW YORK.

COMPOSITION OF MATTER.

1,053,581.

Specification of Letters Patent. Patented Feb. 18, 1913.

Application filed September 21, 1911. Serial No. 650,567.

To all whom it may concern:

Be it known that we, CAMPBELL SCOTT and WILLIAM DEATS, of Yonkers, in the county of Westchester, and in the State of New York, have invented a certain new and useful Improvement in Compositions of Matter, and do hereby declare that the following is a full, clear, and exact description thereof.

10 The object of our invention has been to provide a new composition of matter which, while adapted for many other uses, shall be especially adapted for use as a conducting material for electric apparatus, and to such 15 ends our invention consists in the composition of matter hereinafter specified.

In the accompanying drawings:—Figures 1 and 2 are, respectively, a side elevation partly in section, and a plan view of an electrical contact and holder embodying our invention. Figs. 3 and 4 are similar views of another form of contact and holder embodying our invention. Figs. 5 and 6, are respectively, a plan view and an end view, 25 partly in section, of a bearing sleeve or ring embodying our invention.

Our invention is capable of many different uses, and of embodiment in many different forms, and the embodiments by which 30 we shall illustrate it are therefore to be taken only as typical of many other possible embodiments.

Our desire has been to provide a material which shall combine the qualities of carbon 35 in its various forms with those of various metals, so that a substance will be produced which shall have the qualities of both of such kinds of material. In particular, and for the purpose of electrical contacts, we 40 desire to combine the wearing and lubricating qualities of carbon with the greater conductivity of metal.

The nature of our material will be more fully understood by describing the process 45 by which it is made.

Briefly, the process by which we prefer to make our material consists in impregnating a mass or structure of carbon with a metal in a fluid state. For instance: A 50 piece of wood charcoal may be submerged in metal, and mechanical or fluid pressure applied to the metal to force it into the pores of the charcoal. Or pulverized or 55 powdered carbon or graphite previously molded or pressed into shapes may be impregnated with metal in the manner before

stated. Any desired metal may be used, but when the material is used for electrical conductors where a low resistance is desired, it is preferable to use brass or copper. For 60 electrical contacts, it is preferable to use brass on account of the zinc contained therein, which, when subjected to an arc, has a tendency to vaporize, and a further tendency to disrupt the arc. 65

The process of making our material is the subject of a separate application for patent, No. 618,110, filed March 31st, 1911, to which reference is made for details of operation.

Referring to Figs. 1 and 2, an electrical 70 contact A is formed of carbon or graphite impregnated with metal, and a holder B is formed integral with the impregnating metal. In this manner, the contact and holder are securely fastened together, and 75 electric conductivity between them is made very perfect. A simple and convenient way of forming the holder B on the contact or brush A is to place the carbon or graphite contact in a holder, together with a sufficient 80 quantity of metal thoroughly to impregnate the pores of the contact or brush and also to form the desired holder. The metal may be either melted in the mold or poured into the mold in a molten condition, and while 85 in such condition, pressure may be applied to force a portion of the metal into the contact or brush. When the metal sets, but before it becomes cold, the mold can be 90 opened, and the contact or brush and holder removed, and any metal remaining, which it is not desired to utilize, may be removed by grinding, filing or turning. The mold may be of such a shape as to perfectly fit the contact A and to form the holder, that 95 is, the mold being larger than the contact by precisely the shape which it is desired to have the holder take.

The form of contact and holder illustrated in Figs. 3 and 4 is similar to that in 100 Figs. 1 and 2, except that the brush or contact A' is formed with an annular recess C, which, in the complete article, is, of course, filled with solid metal integral with the holder, thereby assisting in making a firm 105 and reliable connection between the contact and its holder.

Brushes made as above described, with the holder formed in one piece with the brushes are especially valuable in electric railway 110 and elevator service where the practice is to place carbon contacts in separate holders,

from which they sometimes accidentally drop, causing serious damage.

The wearing qualities of our contacts, made by impregnating an ordinary or graphite brush contact with brass, are fully as good as those of the ordinary contacts not so impregnated, and the current carrying capacity for a given rise in temperature is much greater in our contacts. Consequently, smaller sizes of our contacts may be used for the same work as the ordinary contacts of larger sizes, and especially on switches and motors.

The cost of the copper in the commutator segments and slip rings of electrical machinery is one of the most important items in the cost of the materials, therefore by the use of our impregnated brushes, the width of these parts may be reduced, thus greatly lessening the cost.

Our impregnated contacts are so strong that they may be threaded or tapped, and a smooth strong thread obtained, thus making it possible to attach flexible conductors directly thereto without intermediate means as is required with ordinary contacts.

We have found the combination of the qualities of carbon, graphite, or other carbonaceous material with those of the metal to produce a material for bearings and brushings, very desirable.

In Figs. 5 and 6, we have illustrated a bearing sleeve embodying our invention. The sleeve D consists of carbon or graphite impregnated as above described, and, in addition to the metal thus introduced, we have provided radial plugs or parts E formed of solid metal integral with the metal that impregnates the carbon. These plugs of solid metal serve to strengthen the bearings and to support a greater portion of the weight thereon. A simple method of making a bearing of this character is to form a cylindrical block of carbon or graphite with radial holes, preferably placed in staggered relation, as indicated. This block is then placed in a mold and submerged in molten metal, pressure being applied to force the metal into the pores or interstices of the carbon or graphite, and also to fill up the radial holes. When the metal is cool, the impregnated carbon block is taken from the mold, and the surplus metal, if any, removed, leaving a finished bearing.

A metal structure of a higher melting point may be impregnated with a soft metal having a lower melting point, according to

our invention, and both the conductivity and the wearing qualities of such metal structure be increased.

We desire both the particular forms of our material which we have illustrated, and the processes of making the same, to be regarded as typical, and state that we are aware there are many uses to which our material can be put, other than those mentioned.

We claim—

1. An electric contact, comprising a carbon body and continuous lines of metal extending through the interstices between the particles of the carbon and forming therewith a homogeneous mass.

2. An electric contact, comprising a carbon block and metal extending continuously through the interstices between the particles of the carbon and between the holding surface and the contact surface of such block.

3. An electric contact comprising a body of carbon particles in contact with each other, and metal completely filling the interstices between the said particles.

4. An electric contact, comprising a porous carbon body and an interpenetrating metal structure, the particles of each filling the interstices between the particles of the other.

5. A composition of matter, comprising a porous carbon structure and an interpenetrating metal structure each of said structures occupying the interstices between the particles of the other.

6. An impervious compound of intermingled particles of carbon and metal, the particles of carbon being in continuous contact with each other throughout the mass.

7. An impervious compound of intermingled particles of carbon and metal, the particles of carbon being continuous throughout the mass, and the particles of metal also being continuous throughout the mass.

8. The combination of a carbon contact and a metal holder therefor said contact being permeated by lines of metal integral with the holder and extending through the interstices between the particles of the carbon.

In testimony that we claim the foregoing we have hereunto set our hands.

CAMPBELL SCOTT.
WILLIAM DEATS.
